UNITED STATES PATENT OFFICE.

J. H. FISHER, OF PLACERVILLE, CALIFORNIA.

IMPROVEMENT IN RAILROAD-CAR SEATS AND COUCHES.

Specification forming part of Letters Patent No. 30,472, dated October 23, 1860.

To all whom it may concern:

Be it known that I, J. H. FISHER, of Placerville, in the county of Eldorado and State of California, have invented a new and Improved Arrangement of Seats and Berths for Sleeping or Night Cars on Railroads; and I do hereby declare that the following is a full, clear, and exact description of the same, reference being had to the annexed drawings, making a part of this specification, in which—

Figure 1 is a side sectional view of a portion of a railroad-car with my invention applied to it, and shown arranged for day use; Fig. 2, a similar view with the invention arranged for night use; Fig. 3, a transverse section of Fig. 1, taken in the line *xx*; Fig. 4, a section showing one portion of the invention pertaining to the platform-berth.

Similar letters of reference indicate corresponding parts in the several figures.

This invention consists in a novel and improved arrangement of seats and platform-berths, substantially as hereinafter fully shown and described, whereby the seats and platforms may be readily adjusted to form berths to accommodate at night all the passengers which the seats can accommodate during the day.

The object of the invention is to obtain a very simple means or arrangement of parts for effecting the desired end, so that a person unacquainted with the mechanism can readily make the changes from seats to berths, and vice versa.

A A B represent three seats of a railroad-car. The seats A A are constructed precisely alike, being provided with ordinary reversible backs, *a a*, and cushions *b b*, which may be raised, the cushions having each a box, *c*, below them containing pillows *d*. (See Fig. 1.) The center seat, B, differs from the other two in these respects: its back *e* is formed of two longitudinal and equal parts connected by a joint, *f*, which admits of the parts working inward to a certain extent. The cushion *g* may be removed from the frame, and below it a supplemental cushion, *h*, is attached by hinges *i*.

To the frame of the seat B, and underneath the cushion *g*, there is secured by a pivot an arm, *h'*, which may, when required, be turned outward and made to rest on the seat in front of it.

The above parts comprise all the seat arrangements.

The seats are converted into berths as follows: The arm *h'* of the seat B is turned outward and its end adjusted on the frame of the seat adjoining it. The cushion *g* is then removed from the frame of seat B and placed between the frame of the seat B and the frame on which the arm *h* rests, the arm *h*, in connection with a bearing, *i*, at the side of the car, supporting the cushion *g* in its new position. The back *e* of seat B is then reversed in position—that is to say, turned over to the opposite side of the seat—and the supplemental cushion *h* is turned over and made to rest on the frame of the seat next adjoining the cushion *h*, filling the space between the two seats. The back *e* is then turned down in a horizontal position, and a couch or berth equal in length to two seats, A B, and the space between them, in connection with the space covered by the cushion *g*, is obtained. This couch will accommodate two persons, the occupants of one seat. The back *e* is permitted to be adjusted, as described, in consequence of being formed in two parts connected by a joint.

The occupants of the other seat are provided with a berth as follows: At the side of the car, and at the inner ends of the seats A A, there are secured two uprights, C C, in the sides of which grooves *j* are made to receive pins *k* of a platform, D. This platform is allowed to slide freely up and down between the uprights C C, which serve as guides. The inner surface of the platform D is upholstered, and it is of such a width that when fully elevated and turned down in a horizontal position it will project out as far as the outer ends of the seats A A B, as shown in red, Fig. 3. When the platform is adjusted in a horizontal position it is supported at its inner part by studs or pins *l*, attached to the platform, said studs or pins fitting in recesses in the side of the car, as shown in Fig. 3. The outer part of the platform is supported by studs or pins *m*, which rest on brackets *n*, attached to uprights *o o*. The platform D has a head-board, *p*, attached by hinges, so as to admit of its being turned down on the platform when the latter is to be adjusted or moved out of the way between its guides C C; as shown in Fig. 1.

Between the upper parts of the uprights *o o*

there is placed a curtain, E, which is connected by cords q, q' to the platform D, said cords passing over the top and underneath the body of the car, as shown in Fig. 3, so that the curtain will be raised or lowered automatically by the moving of the platform, the curtain being lowered as the platform D is raised in consequence of the pull being on the lower cords, q , or those attached to the lower edge of the platform. When the platform D is lowered between its guides C the curtain will be raised in consequence of the pull on the upper cords, q' .

To the upper or outer edge of the platform D there is attached by arms r a side guard, F. This side guard may be formed of a metal plate or board of sufficient width, the arms r being connected to the ends of the platform and also the guard by pivot s , as shown by the dotted lines in Fig. 3. This manner of attaching the side guard to the platform admits of its being turned up when the platform is adjusted in a horizontal position, (see Fig. 2,) and also admits of the side guard being folded down on the platform, so that the latter may be forced down between the guides C C when required. When the side guard is adjusted in a vertical position it is retained in proper place by pins t , which are attached to it, and by springs u , attached to the uprights $o o$, the pins t being behind the springs u , as shown in red in Fig. 3.

The platform D is provided with one of the pillows d , and the upper or outer edge of the platform has a curtain, a^x , attached, which is concealed by the side guard, F, where the plat-

form is shoved down between the guides C C. This invention may be applied to cars at a small cost, and the mode of adjusting the parts will readily suggest itself to the occupants, so that they may convert the parts into seats or berths, as may be required.

Having thus described my invention, what I claim as new, and desire to secure by Letters Patent, is—

1. The jointed back e of the seat B and the removable cushion g , in connection with the supplemental hinged cushion h , the above parts being arranged in relation with the seats A A, as described, to form the lower berth.

2. The platform D, guides C C, and uprights $o o$, arranged and combined, as shown, to admit of said platform being adjusted in a horizontal position for use or being removed out of the way when not required.

3. The side guard, F, attached to the platform D by means of the arms r , substantially as shown, to admit of the guard being adjusted to the platform, so that the latter may be shoved down between the guides C C, as set forth.

4. Connecting the curtain E to the platform D by means of the cords q, q' , arranged substantially as shown, so that the curtain may be raised and lowered automatically by the movement of the platform.

J. H. FISHER.
